UNITED STATES PATENT OFFICE.

EATON COLE, OF EUREKA SPRINGS, ARKANSAS.

MATCH-DISPENSING DEVICE.

Application filed December 17, 1927. Serial No. 240,632.

This invention relates to match dispensing devices and more particularly to a match safe constructed to discharge a single match at a time.

5 An important object of the invention is to produce a device of this character which may be very readily and cheaply produced and which will be durable and efficient in service.

10 A further object of the invention is to provide a device of this character which, in addition to serving as a match safe and dispensing device for matches, may likewise be employed as a receptacle for burnt matches, 15 ashes and the like.

These and other objects I attain by the construction shown in the accompanying drawings, wherein for the purpose of illustration is shown a preferred embodiment of 20 my invention and wherein:—

Figure 1 is a perspective view of a match dispensing device constructed in accordance with my invention;

25 Figure 2 is a section on the line 2—2 of Figure 1;

Figure 3 is a section on the line 3—3 of Figure 2;

30 Figure 4 is a fragmentary side elevation of the extension which operates in the groove of the base;

Figure 5 is a fragmentary bottom plan view of the match safe.

Referring now more particularly to the drawings, the numeral 10 generally designates a base which, in accordance with my invention, is provided with longitudinally extending parallel slots 11 opening through the upper face thereof and having their lower ends enlarged, as indicated at 12.

40 Extending transversely of the base at the center thereof is a groove 13 of a size just sufficient to receive a single match and the base at its center and interrupting the groove has a depression 14 into which the fingers 45 may be inserted to readily engage a match disposed in this groove. The bottom of the base is provided with a sanded match scratching surface S.

The numeral 15 generally designates a 50 match receptacle which is in the form of a rectangular tube of just sufficient size to admit a box of the type in which matches are ordinarily vended. This receptacle is open-bottomed and has at the lower ends of its 55 end walls 16 extensions 17 for projection into the slots 12. The lower ends of these

extensions are provided with a scroll or roll 18 adapted to operate in the enlargement 12 of the slots and considerably wider than the end walls of the receptacle, so that the receptacle is held against vertical displacement or tipping in the slots. Opposite side walls of the receptacle are provided adjacent their lower ends with vertically extending slots or sight openings 19, enabling the user to determine when the matches are practically exhausted and an end wall 16 has an opening 20 formed therein adjacent its lower end through which a single match may be inserted to the receptacle. The base at opposite ends thereof is provided with stops 21 preventing the receptacle from moving from the base.

To fill the receptacles with matches, the device is bodily tilted to a horizontal or inverted position and a box of matches from which one end has been removed is replaced therein with the open end foremost. The device is then rotated and the box removed, leaving the matches in the receptacle within which they may move freely downwardly, due to the clearance space afforded by the removal of the box. The follower is then placed upon the top of the matches. Matches are dispensed by sliding the casing 80 from one side to the other of the slot, a match being deposited in the groove 13 in the passage of the receptacle. Burnt matches, cigarette stubs or the like may be placed in the upper end of the casing upon 85 the follower 22. The sanded bottom surface of the base affords both the scratching surface and a means for holding the base stationary as the receptacle is slid thereon.

It will be obvious that while I have described a particular method of connecting the receptacle and base to one another for sliding movement in a fixed path, other means might be resorted to to attain this end. I accordingly do not limit myself to 90 such specific structure except as hereinafter claimed.

I claim:—

1. In a match safe and in combination, a 105 base having parallel slots, an open-bottomed receptacle seated upon the upper surface of the base and having portions extending into said slots and having engagement therewith preventing vertical movement of the receptacle with relation to the base while permitting reciprocatory motion thereof longitudinally of the base, said base having a 110

groove extending transversely with respect to said slots and of a depth to receive a single match.

2. In a match safe and in combination, a base having parallel slots, an open-bottomed receptacle seated upon the upper surface of the base and having portions extending into said slots and having engagement therewith preventing vertical movement of the receptacle with relation to the base while permitting reciprocatory motion thereof longitudinally of the base, said base having a groove extending transversely with respect to said slots and of a depth to receive a single match, said grooves opening through the ends of the base and means upon the base limiting sliding movement of the receptacle upon the base.

3. In a match safe and in combination, a base, parallel slots opening through the upper surface of the base and having enlargements at their lower ends, said slots opening through the ends of the base, an open-bottomed receptacle having its side walls extended downwardly below the bottom thereof and provided with scrolls adapted to enter the enlargements of the

slots while the extensions of the side walls are operating in the slots and the base further having a transversely extending groove connecting said slots and removable stops carried by the base at the upper surface thereof between said slots and at the ends thereof.

4. In a match safe and in combination, a base, parallel slots opening through the upper surface of the base and having enlargements at their lower ends, said slots opening through the ends of the base, an open-bottomed receptacle having its side walls extended downwardly below the bottom thereof and provided with scrolls adapted to enter the enlargements of the slots while the extensions of the side walls are operating in the slots and the base further having a transversely extending groove connecting said slots, and removable stops carried by the base at the upper surface thereof between said slots and at the ends thereof, said scrolls being of greater width than the side walls of the receptacles.

In testimony whereof I hereunto affix my signature.

EATON COLE.
